UNITED STATES PATENT OFFICE.

IRA EDWIN MARSH, OF NEWARK, OHIO, ASSIGNOR TO THE DWYER BROS. & CO., OF COLUMBUS, OHIO.

COMBINATION MUSICAL INSTRUMENT.

1,256,487.

Specification of Letters Patent. Patented Feb. 12, 1918.

Application filed March 2, 1916. Serial No. 81,706.

To all whom it may concern:

Be it known that I, IRA EDWIN MARSH, a citizen of the United States, residing at Newark, in the county of Licking and State of Ohio, have invented certain new and useful Improvements in Combination Musical Instruments, of which the following is a specification.

The present invention appertains to improvements in combination musical instruments designed to enable said instruments to be played synchronously and harmoniously or each independently of the other.

To best obtain a comprehension of the objects to be attained by my invention, it is here noted that I am aware of the fact that it has been heretofore proposed to produce a combination of musical instruments as above broadly indicated, but this has been done generally by devising a special construction of the instruments themselves involving considerable expense in their manufacture and greatly sacrificing simplicity of coöperative parts. Hence, it has been my primary object to provide means capable of attachment to standard instrumentalities of one type of instruments for operating a second instrument of a different type by means of said instrumentalities whereby to permit of the conjoint or independent actuation, as hereinbefore premised.

More specifically speaking in carrying out the invention I employ an attachment arranged in coöperative relation with respect to a piano action operable thereby to control the pressure actuating devices of a pipe organ, means also being provided for quickly connecting and disconnecting the attachment so that one of said instruments only may be played, at the will of the operator.

These and such other objects as may hereinafter appear are attained by the novel construction, combination, and arrangement of parts to be hereinafter specifically described and claimed. Reference will now be had to the accompanying drawings forming a part of this specification, wherein:

Figure 1 is a vertical sectional view of a piano of conventional type having my attachment applied thereto.

Fig. 2 is an enlarged fragmentary view of the attachment and its coöperating parts.

Fig. 3 is a fragmentary sectional view of a port block used in this apparatus.

Fig. 4 is a fragmentary perspective view

showing more clearly the arrangement of the valve operating means constituting the main feature of this invention.

Fig. 5 is a sectional view through the organ actuating instrumentalities combined with my operating means for playing the organ.

Fig. 6 is a detail view.

Throughout the following detail description, and on the several figures of the drawings, similar parts are referred to by like reference characters.

In addition to the foregoing general remarks as to the objects of this invention, it may also be stated that there exists at the present time a demand, among motion picture houses, for instance, for some means for producing pipe organ effects, and this without employing an automatic or mechanically operated instrument, and as will be seen in the following description, this demand is met by providing an organ played and controlled by the pianist from the manually operated keyboard of a piano.

Referring to the drawings, 1 indicates a piano case of conventional type, 2 the piano action therefor and 3 its manually operable piano keys. To such instrument I apply the operating means which forms the main feature of this apparatus, and which means consists of a suitable supporting bar or rail 4 hingedly mounted upon the supporting brackets 5 intermediate the piano keys 3 and the piano action 2 as clearly shown in Fig. 1 of the drawing.

The rail 4 carries thereupon a plurality of port blocks 6 attached to the rail in any suitable manner and projecting from its rear edge slightly so as to bring a spring 7 secured to the surface of each block directly adjacent to a sticker 8 of the piano action. Each valve block is provided with a vent tube 9 normally held closed by the spring 7 which is suitably washered at 7' so as to afford a proper closing means to prevent the escape of pressure which is led to the port blocks 6 through the operating ducts or pipes 10. It will be understood that there is provided one of these port blocks for each piano sticker for a suitable number of octaves of the piano action to properly carry out the object of this invention, and each of said port blocks is provided with one of the operating ducts 10 as above referred to communicating with the 110

organ actuating instrumentalities herein-after more particularly described. Each of the piano stickers 8 is provided with a projection of any desired form as indicated at 5 11 arranged beneath the projecting extremity of the spring 7 so that it may co-operate therewith when the sticker is operated by the piano key for the purpose of venting the proper duct of the organ ac- 10 tion. The rail 4 and its port blocks, for convenience of description will be herein-after referred to, as the valve attachment and this attachment is designed to be operated by the pianist so as to operatively 15 connect or disconnect the same to produce the combined or independent action of the organ and the piano as will now be described.

Arranged beneath the bed 12 of the piano 20 is a lever 13 pivotally mounted at 14 intermediate its length. The rear end of this lever is connected by the rod 15 to one end of the valve attachment and by means of this bar or lever the rail 4 may be raised 25 so as to move the valve springs 7 out of the path of the sticker projections 11, thereby preventing the operating ducts 10 from being opened or exhausted. This lever 13 is so positioned as to be readily operated by 30 the knee of the pianist, being normally held at its outer end by a spring actuated catch 16 for holding the valve attachment down in operative position with relation to the piano action when the organ is played. The 35 bar, however, is provided with a spring 17 so that when relieved from the catch 16, said lever will be automatically depressed at its outer end to raise the valve attachment in the manner hereinbefore set forth when 40 the organ is not played.

Referring now to Figs. 4 and 5, it will be observed that the operating ducts 10 leading from the valve attachment communicate with an organ valve action chest 18 which 45 is located at any convenient place with respect to the piano. I desire it to be understood that the organ instrumentalities are shown in the drawings conventionally and they are subject to arrangement or dispo- 50 sition with reference to the piano as may be required in the particular installation of this element or instrumentality.

The valve action chest is provided with air pressure in the compartment 19 by any 55 suitable pressure supplying means not illus- trated in the drawings, said compartment 19 preferably communicating with the organ wind chest 20 through the duct 21 so that the same pressure which is supplied to said 60 wind chest through the duct 22 may be utilized for the valve action chest also. In the usual manner the organ wind chest connects with the organ pipes 23, each of said pipes being normally maintained closed with 65 respect to the wind chest by means of a

valve 24 covering the pipe port. This valve is carried at one end of a lever 25 suitably supported upon the upper wall of the chest by the bracket 26 and having a spring 27 arranged to hold the valve 24 normally in 70 closed position. The other end of the lever 25 has connected thereto a valve rod 28 extending through the bottom of the wind chest and terminating at its lower end in superposed relation to a pouch 29 on the 75 upper surface of the organ action chest 18. Said pouch covers a passage 30 in the chest and with which a lateral passage 31 com- 80 municates at one end. The other end of the passage 31 communicates with the air passage 32 which is provided with a conventional form of double valve 33 consisting of the upper valve disk 34 and the lower valve disk 35 adapted to be alternately seated on the ends of the air passage to estab- 85 lish communication between the channel 31 and either the atmosphere or the pressure chamber 19. This valve 33 is held by the air pressure in the chamber 19 with the pas- 90 sage 32 closed and a spring 36 connected to 95 said valve assists in the quick action of the valve in a manner readily understood by those skilled in the art to which this invention refers. The lower end of the valve is connected to a diaphragm 37 arranged over 100 a small recess 38 with which one of the operating ducts 10 communicates. Air pres- 105 sure is supplied from the chamber 19 to the recess 38 by the pin hole feed or passage 39 so that the pressure causes the diaphragm 100 to normally assume the position shown in Fig. 5.

With the foregoing description in view the cycle of a single operation will now be set forth. Upon the depression of a piano key 105 3 the respective sticker 8 of the piano action coacting therewith will be raised and by reason of the normal position of the valve attachment a spring 7 of a port block 6 will also be simultaneously actuated. The pres- 110 sure in the duct 10 leading from the recess 38 beneath the diaphragm 37 of the corre- 115 sponding organ element will be released causing the sudden collapse of said dia- phragm and the simultaneous unseating of 115 the valve 35 immediately allowing the pres- 120 sure from the chamber 19 to pass through the channel 31 to the pouch 29, thereby rais- 125 ing the pouch and the valve rod 28 finally actuating the lever 25 and opening the organ pipe valve 24 whereupon this pipe is sound- 130 ed. This action takes place obviously throughout the playing of the piano so that said piano and organ are simultaneously operated. When it is desired to disconnect the organ either permanently or temporarily, the pianist releases the outer end of the lever 13 from its catch, causing the valve rail 4 to be lifted and the port blocks moved into a position such as shown in dotted lines in 130

Fig. 2 where they are out of the path of actuation by the piano sticker. The piano alone may now be played.

When it is desired to play the organ alone, 5 through the instrumentality of the piano keys, the valve attachment is lowered again into the position hereinbefore described, and a muffler rail 40 is lowered in front of the hammers of the piano action so as to prevent 10 sounding of the piano keys. This rail is operated in any desired manner by the pianist such for instance through the instrumentality of a pedal 41 connected by a rod 42 to the lever 43, said lever carrying the 15 muffler rail 40 at its rear extremity. It will thus be apparent that only a single set of operating keys is required to enable the operator of this apparatus to play either instrument independently or both instruments 20 simultaneously.

One of the desirable features of my valve attachment is the fact that it is capable of installation as a unit into a conventional form of piano as hereinbefore mentioned, the 25 operating ducts coacting therewith being led through a small opening in the back of the piano and the supporting parts for the valve attachment being easily attached to the piano case without altering materially the 30 construction of the piano. It follows that where such instrument is usually provided it is not necessary, in installing the combination comprehended by this description, to displace the said conventional piano for any 35 specially constructed one resulting in a considerable saving of expense by reason of this adaptability.

Having thus described my invention, what I claim as new is:

40 1. The combination with piano stickers and manually operable keys therefor and pneumatic organ instrumentalities, of valve means disposed adjacent to the piano stickers and operable by said stickers for controlling the organ instrumentalities, and means for shifting the valve means bodily into and out of operative relation with respect to the piano stickers.

2. The combination with a piano action, a 50 keyboard therefor and organ instrumentalities, of detachable members separate from the keyboard and projecting from the action elements operated by the keys of said keyboard, a unitary control device for the organ instrumentalities consisting of an attachment arranged above the keyboard and contiguous to said detachable members in the path of movement thereof when playing the piano, and means for bodily moving the at-

tachment away from the projecting members to render the organ instrumentalities inoperative with respect to those of the piano at the will of the operator.

3. In combination, piano action including vertical hammer actuating members, 60 piano keys therefor, projections on said vertical members, a valve attachment for operating organ instrumentalities comprising a valve rail pivotally mounted at one side and arranged to cooperate with the 65 projections mentioned, and means for pivotally moving the rail into inoperative position comprising a lever disposed beneath the piano keys and pivoted intermediate its length and a connection intermediate the 70 lever and the free side of the valve rail whereby the latter may be elevated.

4. In combination, a piano action and keys therefor, organ instrumentalities including a valve action, an attachment for 80 the piano for controlling the operation of said organ instrumentalities comprising a rail arranged adjacent to the piano action, a series of individually separable valve blocks secured to said rail and operable 85 by the piano action elements, means establishing communication between said valve blocks and the organ valve action, and means for raising the rail to render the 90 valve blocks inoperative.

5. In combination, a piano action including vertically arranged stickers, and keys for operating said action, organ instrumentalities including a valve action, a unitary attachment consisting of a valve rail 95 arranged over the rear portion of the piano keys aforesaid, venting instrumentalities carried by said rail and projecting into contiguous coacting relation to the piano action stickers aforesaid, means on said stickers adapted to coact with the venting instrumentalities during operation of the piano action keys, and means for lifting the venting instrumentalities out of the path of movement of the means carried by 100 said stickers to render said venting means inoperative.

6. In combination, a piano action and an organ valve action, operating means intermediate said actions comprising a valve 110 rail, supporting means to which said rail is pivotally connected, means for shifting said valve rail consisting of a lifting member adapted for manual operation, and means for holding said rail in operative and inoperative positions.

In testimony whereof I affix my signature.
IRA EDWIN MARSH.
